US0D1005297S

(12) **United States Design Patent** (10) **Patent No.:** **US D1,005,297 S**
(45) **Date of Patent:** **** Nov. 21, 2023**

(54) **CASE FOR PORTABLE DISPLAY DEVICE**

(71) Applicant: **Apple Inc.**, Cupertino, CA (US)

(72) Inventors: **Jody Akana**, Los Altos Hills, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans**, San Francisco, CA (US); **Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/884,386**

(22) Filed: **Feb. 10, 2023**

Related U.S. Application Data

(63) Continuation of application No. 29/825,326, filed on Jan. 31, 2022, now Pat. No. Des. 978,153, which is a continuation of application No. 29/784,011, filed on May 17, 2021, now Pat. No. Des. 942,459, which is a continuation of application No. 29/679,892, filed on Feb. 11, 2019, now Pat. No. Des. 920,335, which is a continuation of application No. 29/586,557, filed on Dec. 5, 2016, now Pat. No. Des. 840,405, which is a continuation of application No. 29/500,365, filed on Aug. 25, 2014, now Pat. No. Des. 773,454, which is

a continuation of application No. 29/415,927, filed on Mar. 15, 2012, now Pat. No. Des. 713,402, and a continuation-in-part of application No. 29/415,035, filed on Mar. 6, 2012, now abandoned, which is a continuation of application No. 29/415,062, filed on Mar. 7, 2012, now Pat. No. Des. 688,251, which is a continuation of application No. 29/415,035, filed on Mar. 6, 2012, now abandoned.
